UNITED STATES PATENT OFFICE.

JOHN S. CARPENTER, OF IRVINGTON, NEW JERSEY, ASSIGNOR TO WORTHINGTON
PUMP AND MACHINERY CORPORATION, OF NEW YORK, N. Y., A CORPORATION
OF VIRGINIA.

HYDRAULIC TURBINE.

Application filed September 21, 1921. Serial No. 502,267.

To all whom it may concern:

Be it known that I, JOHN S. CARPENTER, a citizen of the United States, residing at Irvington, county of Essex, and State of New Jersey, have invented certain new and useful Improvements in Hydraulic Turbines, fully described and represented in the following specification and the accompanying drawings, forming a part of the same.

10 This invention relates to improvements in hydraulic turbines.

The object of the invention is to provide a turbine which will have a high efficiency, with a compact construction, while at the same time those parts of the turbine most subject to wear may be replaced without dismantling the whole turbine.

With this object in view, and some others which will be apparent to those skilled in the art from the description hereinafter, a structure embodying all the features of the invention comprises a turbine in which the line of flow of the inlet water is deflected before it strikes the runner, in combination with gates, which, when open, overhang at their inner ends, that is, project into the runner chamber, the overhanging end or ends of each gate being chamfered, beveled or otherwise gradually reduced in thickness so as to form a stream line surface for the deflected water; also, it comprises a turbine in which the cover plate is supported independently of the gate mechanism, so that in case of injury to the gates or any of them, the casing cannot collapse, while at the same time the gate mechanism is such that the gates may be readily withdrawn without dismantling the turbine, in combination with means for preventing loss of efficiency due to the use of means for supporting the casing outside the gates; also it comprises a special construction of the bottom member whereby the wear on the internal portion of said bottom member is reduced while at the same time the parts most subject to wear may be replaced without dismantling the turbine.

The invention will first be described in connection with the accompanying drawings and then more particularly pointed out in the claims.

In the drawings:—

Fig. 1 is a section partly in elevation of a hydraulic turbine embodying the invention;

Fig. 2 a detail plan view of the top of the turbine;

Fig. 3 a section on the line 3—3, Fig. 1;

Fig. 4 a plan view of the internal bottom ring;

Fig. 5, 6 and 7 detail views of a turbine gate, and

Fig. 8 a sectional view of another type of turbine embodying the new gate construction.

Referring to the drawings, it will be seen that the turbine comprises a runner having a hub A, blades B and a band C, the runner being supported by and serving to drive a turbine shaft D. The runner is mounted 70 within a casing comprising a bottom member E and a top member or cover plate F.

The bottom member in the best embodiment of the invention comprises a curb ring e' with a series of upwardly extending ribs 75 e² carrying a bottom plate which comprises two parts, namely, an external bottom ring e³ and an internal removable bottom ring e⁴. The external bottom ring e³, the ribs e² and the curb ring e' are advantageously cast in 80 one piece, while the internal removable bottom ring e⁴ is fitted into a shelf or shoulder in the external bottom ring e³ and secured in place in any suitable way to permit detachment, as for example by means of countersunk machine screws, indicated at e⁵, which are accessible from the inlet of the turbine.

For convenience of removal this internal ring may be made in sections or segments 85 having downwardly extending lugs at the ends, the segments being bolted together at the lugs by suitable bolts, as will be clear from Fig. 4 of the drawings.

The curb ring e' is provided with a bottom flange 1 arranged to rest upon the foundation, usually of concrete, the curb ring being grouted into this concrete foundation.

In the best embodiment of the invention the runner blades B are made of wrought steel plate material forged hot to the correct shape and inserted in the mold in which the hub A and band C are cast, so that, in this way, the runner is constructed as one integral unit, yet has blades of such accurate 100 form and surface finish as to give high efficiency.

The hub may be formed in any suitable way, but for lightness and strength, it is very advantageous to make the hub hollow 110

and provide it with interior radial strengthening ribs, as indicated at 2. This can be done in casting the hub, for which reason it is provided with an opening at its lower end, 5 as shown, which also provides, for the escape of leakage water from above the runner.

The runner band C is provided on the outside of its upper end with a rebate, indicated at 3, to receive a downward extending flange 10 4, carried by the internal removable bottom ring e^4 .

The inner surface of the runner band C and the internal bottom ring e^4 are curved near their meeting faces, as indicated at 5, 15 to allow the water to make its turn here in the proper manner without unnecessary loss of energy and therefore without any appreciable cutting of the band or said ring.

The inner surface of the runner band C 20 instead of being cylindrical is curved or sloped outward in the direction of the water flow, whereby loss of energy by eddying is avoided.

The runner hub A is secured to the turbine 25 shaft D in a special manner. Instead of being splined to the shaft as usual, it is provided with a central opening into which the reduced end of the shaft projects, while the shaft itself has a radial flange or collar 30 d extending over the central portion of the top of the hub and secured to it by any suitable means, as for example, by the machine screws indicated at 6 which are accessible from the top. The cover plate F has a central opening whose diameter is greater than the flange or collar d on the shaft, so that the latter may pass through this opening. The opening is covered by a bearing plate G carrying the main bearing or journal box 35 40 H for the turbine shaft D. The bearing plate is provided with a downward extending rib 7 which fits snugly in the opening in the cover plate, and suitable means is provided for holding the bearing plate G to the cover plate F, as, for example, the machine screws 7'.

The journal box H has a liner or bushing h of suitable anti-friction metal cast into dovetail openings in the journal box as will 50 be clear from the drawings. Annular spaces are provided below and above the liner or bushings, as indicated at 8 and 9, respectively, these spaces being connected by a suitable passage formed in the journal box, 55 as indicated at 10, in order that any suction which may act at the lower end of the liner will be compensated by a corresponding suction at the upper end of the liner, thereby 60 overcoming the tendency of the grease or other lubricant to be sucked out of the bearing and down into the wheel. For the purpose of supplying lubricant to the bearing, the latter is provided with an opening at its center on one side, with which communicates 65 a grease pipe α conducting grease from a

suitable source, as, for example, a grease gun (not shown).

To prevent the entrance of sand or the like into the upper end of the bearing, a bearing cap or sand collar I is provided, 70 this being made in two halves screwed together, as shown, and fitting tightly to the shaft. It has a flange extending downward outside the upper end of the journal with which it makes a running fit. 75

The cover plate F is recessed or dished upward at its center portion to receive the upper end of the runner hub while the inner or under surface of the cover plate and the crown or outer surface of the runner hub are suitably curved, so as to deflect the inflowing water in an efficient manner, as will be clear from the drawings. 80

The cover plate F is supported from the foundation, through the external bottom ring e^3 by a series of column bolts, as indicated at K, which in the present example are shouldered as shown so as to space the cover plate and bottom member at the proper distance apart. 85

The lower end of each column bolt is threaded into a boss cast integral with the external bottom ring e^3 , as indicated at 11, while the top end passes through a similar boss 12 carried by the crown plate and is provided with a nut as shown. 90

It is well known that there are many advantages in supporting the cover plate independently of the gate bolts, but it has been recognized that with such independent supporting means there is serious loss due to eddy currents formed by such supporting means. 95

In order to obtain all the advantages of such independent supports as the column bolts K, and at the same time avoid the disadvantages thereof, I provide each column bolt with a swinging guide vane L 100 whose sides have stream line configurations. Since these guide vanes are free to swing on their respective column bolts, they are readily adjusted by the water currents so

as to lead the water to the gates of the turbine without loss of efficiency. That is, the guide vanes conform at all times to the direction of the entering water, which, of course, may vary according to the amount to which the turbine gates are opened. 105

To limit the movement of the guide vanes suitable stops are provided, as, for example, the stop pins 7, 7' in Figs. 1 and 3. For the sake of lightness the guide vanes may be 110 made hollow as shown in the drawings, and preferably will be of wrought metal. The number of column bolts and guide vanes should be sufficient to insure the proper

strength of support for the crown plate and the load which it carries. However, in practice about half as many column bolts as there are gates will be sufficient. Also, it is 115 very advantageous to locate each column bolt on a radial line which cuts the circum-

120

125

130

ference on which the axes of the gates are located about one fourth the distance between the axes of two such gates. That is, a column bolt is not in a radial line with 5 the axis of the nearest or adjacent gate, nor on a radial line with either end of such gate in its closed position, but is about on a radial line intersecting the tail portion of the gate when the latter is in its widest open 10 position.

As the crown plate is supported on the column bolts it becomes possible to mount the gates between the bottom member and the crown plate in such a way that the gates 15 may be removed individually in a sidewise direction, thereby avoiding the necessity of dismantling the wheel. While this removability may be obtained in various ways, in the preferred embodiment of the invention 20 each gate M is mounted on a pin or spindle M' which has its lower end suitably journaled in the bottom member, and has its upper end extending through a journal bearing carried by the crown plate. The upper 25 end extends sufficiently above this journal bearing to permit the attachment of the gate operating device. Suitable means is provided for connecting the gate to its spindle so that it cannot rotate thereon, while at 30 the same time allowing the spindle to be withdrawn from the gate. In the embodiment shown in the drawings the spindle is stepped, that is to say, has several different diameters, the smallest diameter being at 35 the lower end to fit in a headed or flanged bronze bushing 18 removably inserted in a counter-bored socket in the internal removable bottom ring e². The top of this socket projects slightly above the top face of the 40 ring e² in order to keep the gate from bearing on the bottom member. The portion of the spindle having the next larger diameter passes through an opening in the bottom transverse brace 14 of the gate. The third 45 diameter of the spindle, constituting the main part of it, fits in an opening in the upper transverse brace 15 of the gate. This part of the spindle is provided with a feather, as indicated at 16, which is arranged to fit 50 into a slot formed in the upper transverse brace 15, thereby preventing rotation of the gate with relation to its spindle. The radial extension of the feather 16 is not greater than the radius of that part of the 55 spindle just above the gate, so as to permit the ready withdrawal of the spindle in an upward direction.

The journal bearing for the spindle carried by the crown plate comprises a bushing 17, preferably of bronze, removably inserted in an opening in a boss formed on the crown plate, as will be clear from the drawings.

The construction and location of the gates 60 relative to the wheel constitute an important

feature of the invention. It has heretofore been considered a disadvantage to have the end of the gate project inside the bottom member because of the eddy currents formed in the space directly under the projecting 70 end of the gate. Hence, owing to the necessity of having a gate of sufficient width to properly guide the water to the runner and the additional necessity of not having the gate project beyond the inside of the 75 bottom member it has been considered necessary to make the casing somewhat larger than otherwise would be required. While the turbine as heretofore described may use this old arrangement of the gate, an important feature of the invention consists in arranging the gates closer to the center and allowing their inner edges to project inside and overhang the inner edge of the bottom member, while overcoming the disadvantages 80 of the prior similar arrangements by cutting down the thickness of the overhanging corners so that the sides of the gates at these corners have substantially stream line surfaces in the direction of the water as it 85 turns down at the inside edge of the bottom member. The reduced portion of the gate is indicated at m and will be understood from Figs. 5 to 7.

While this feature of the invention is 90 needed only at one corner of the gate in the turbine heretofore described it may be applied to both the overhanging corners in a double flow turbine, as is illustrated for example in Fig. 8. In this figure the gate is 95 marked M² and the reduced corners are indicated at m².

Suitable mechanism is provided for actuating all the gates simultaneously to adjust 100 said gates as may be required. In the present example each spindle M' projects above its top bearing, and the projecting end is advantageously reduced in diameter to form a shoulder. On the reduced end is clamped 105 one end of a gate lever, N, having its other end extending inward and pivotally connected to one end of a link, O, which has its other end pivoted to a gate adjusting 110 ring P rotatable around and in contact with an upward extending annular flange or hub 115 18 carried by the cover plate.

Suitable means are provided for lubricating the contacting surfaces of the hub 18 and gate adjusting ring, P, as, for example, by providing a grease cup 19 discharging 120 through channels as shown in Fig. 1.

The gate levers N are connected to their respective spindles only by the frictional grip of the lever on the spindle, so that in case any obstructions should lodge in the 125 gates preventing the closing of a gate, the lever N for such gate will slip on its spindle instead of either breaking the gate or lever or preventing the closing of the other gates. In order to provide the necessary construc- 130

tion for the purpose stated each lever N has its end split and is provided with a machine screw or bolt n to draw the two parts together thus clamping the spindle with such

5 force as may be required.

The gate adjusting ring P is arranged to be operated in any suitable way. Usually it is controlled by a governor mechanism (not shown) which operates a rod pivotally 10 connected to the ring. One end of such a rod is indicated at R.

It is to be understood that the invention is not to be limited to the specific embodiments hereinbefore described and shown in 15 the drawings, as many changes may be made without departing from the spirit of the invention so long as the construction is within the scope of the following claims.

What is claimed is:

20 1. In a hydraulic turbine, the combination, with a runner, a bottom member, and a cover plate, of gates pivotally mounted between the bottom member and the cover plate, column members arranged outside the 25 gates for holding the cover plate from the bottom member, and a swinging guide vane journaled on each column member and arranged to adjust itself to the water flow.

2. In a hydraulic turbine, the combination, with a runner, a bottom member, and a cover plate, of gates pivotally mounted between the bottom member and the cover plate, means for adjusting the gates to determine the flow of water to the runner, column members arranged outside the gates for holding the cover plate from the bottom member, and a guide vane journaled on each column member, said guide vanes being arranged to be changed in position 35 upon the adjustment of the gates.

3. In a hydraulic turbine, the combination, with a runner, a bottom member, and a cover plate, of gates pivotally mounted between the bottom member and the cover plate, column members arranged outside the gates for holding the cover plate from the bottom member, and a swinging guide vane journaled on each column member and arranged to adjust itself to the water flow, 45 each guide vane having stream line sides.

4. In a hydraulic turbine, the combination, with a runner, a bottom member and a cover plate, of gates pivotally mounted between the bottom member and the cover plate, column members arranged outside the gates for holding the cover plate from the bottom member, and a swinging guide vane journaled on each column member and arranged to adjust itself to the water flow, 55 the column members being less in number than the number of gates.

5. In a hydraulic turbine, the combination, with a runner, a bottom member and a cover plate, of gates pivotally mounted 60 between the bottom member and the cover

plate, column members arranged outside the gates for holding the cover plate from the bottom member, and a swinging guide vane journaled on each column member and arranged to adjust itself to the water flow, 70 the column members being out of line radially with the pivotal axes of the gates.

6. In a hydraulic turbine, the combination, with a runner, a bottom member and a cover plate, of gates pivotally mounted 75 between the bottom member and the cover plate, shouldered column bolts arranged outside the gates for holding the cover plate from the bottom member, and a swinging guide vane journaled on each shouldered 80 column bolt and arranged to be adjusted automatically to the water flow.

7. In a hydraulic turbine, the combination, with a runner, a cover plate and a bottom member comprising an external bottom ring and a removable internal bottom ring comprising a plurality of separately removable segments, of a series of spindles journaled in the internal bottom ring and cover plate respectively and arranged to be 90 withdrawn from the outside of the case, a plurality of gates through each of which one of the spindles extends, means for locking the gate to the spindle, and column members outside the gates and arranged 95 to support the cover plate from the external bottom ring.

8. In a hydraulic turbine, the combination, with a bottom member comprising an external bottom ring, of an internal bottom ring formed of a plurality of sectors, said internal ring being detachably connected to the external bottom ring, a series of spindles journaled in the internal bottom ring and cover plate respectively and 100 arranged to be withdrawn from said ring and plate in an axial direction, a plurality of gates through each of which one of the spindles extends, means for providing a locking engagement between each gate and 105 its spindle, and column members outside the gates and arranged to support the cover plate from the external bottom ring, said column members being spaced apart a sufficient width to permit the removal of a gate 110 through the spaces between them.

9. In a hydraulic turbine, the combination, with a casing having a water inlet and a runner inside the casing and having its axis of rotation at angles to the direction 115 of flow of the water through the inlet, of gates arranged to control the water to the runner and having overhanging corners substantially as described, each overhanging corner being gradually reduced in 120 thickness from the body of the gate toward said corner to form a stream line surface on each side conforming to the changing direction of flow of the water in its passage 125 from the inlet to the runner.

10. In a hydraulic turbine, the combination, with a cover plate, and a runner having a band, of a bottom plate meeting said band, the meeting corners of the band and bottom plate being curved in cross-section, substantially as described, and a plurality of gates mounted between the cover plate and the bottom plate, each gate having a corner arranged to extend over the curved

portion of the bottom plate when the gates 10 are not closed, the said corners of the gates being hollowed out to form stream line surfaces in the direction of flow of the water at said corners.

In testimony whereof, I have hereunto 15 set my hand.

JOHN S. CARPENTER.
